STRINGED MUSICAL INSTRUMENT

Francis C. Hall, Newport Beach, Calif., assignor to Electro String Instrument Corporation, Santa Ana, Calif., a corporation of California

Filed Sept. 26, 1966, Ser. No. 4,016

Term of patent 14 years

(Cl. D56—1)

FIGURE 1 is a plan view of a stringed musical instrument showing my new design;

FIGURE 2 is a side elevational view thereof;

FIGURE 3 is a rear view thereof;

FIGURE 4 is an end view thereof;

FIGURE 5 is a fragmentary view in plan showing in detail the ornamental design of the rear of the stringed musical instrument taken within the encircled area "5" in FIG. 3, and

FIGURE 6 is a fragmentary view in elevation illustrating on an enlarged scale the tail piece as shown in FIGURE 2 with the knobs illustrated in FIGURE 2 omitted for clarity.

I claim:

The ornamental design for a stringed musical instrument, substantially as shown and described.
